UNITED STATES PATENT OFFICE.

JAMES BATE, OF YPSILANTI, MICHIGAN.

DIE-CASTING MACHINE.

1,292,679.

Specification of Letters Patent. Patented Jan. 28, 1919.

Application filed September 13, 1918. Serial No. 253,884.

To all whom it may concern:

Be it known that I, JAMES BATE, a citizen of the United States, residing at Ypsilanti, in the county of Washtenaw and State 5 of Michigan, have invented new and useful Improvements in Die-Casting Machines, of which the following is a specification.

This invention relates to die casting machines, the object in view being to produce 10 a machine which will greatly facilitate the operation of casting dies, with the aid of compressed air, means being provided for heating the metal contained in a suitable receptacle forming a part of the machine, and 15 means being also provided for forcing the molten metal from such receptacle to the die or dies at any desired moment.

A further object of the invention is to provide means for intermittently filling the 20 molten metal receptacle by allowing the molten metal to flow by gravity into such receptacle, the device embodying a heating hopper in which the molten metal is contained before it is allowed to flow into the 25 above mentioned molten metal receptacle.

With the above and other objects in view, the invention consists in the construction, combination and arrangement of parts, as herein described, illustrated and claimed.

30 The accompanying drawing represents a view partly in elevation and partly in vertical section of the die casting machine.

The die casting machine of this invention comprises a hopper or pot 1 for the molten 35 metal, said hopper being preferably of cupped formation as shown and formed in the side wall thereof with an outlet conduit 2 which terminates in a plurality of nozzles 3, one or both of which may be used. Ordinarily, only one nozzle 3 is used, the other nozzle being plugged. This enables either 40 nozzle to be used according to the convenience in passing the molten metal onward to the die. The pot or hopper 1 is formed 45 in the bottom thereof with a metal receptacle 4 of a predetermined size, sufficient to contain the proper amount of metal to charge or fill one die. The upper edge of the receptacle 4 extends above the bottom of the hopper 1 and terminates in a beveled and machined edge or face 5, the purpose of which 50 will presently appear. The bottom of the receptacle 4 is in communication with the receiving end of the outlet conduit 2. Arranged 55 below the hopper 1 and the receptacle 4 is a burner 6 to maintain the contents of

the hopper 1 and the receptacle 4 in a molten state. A jacket 7 surrounds the hopper and receptacle 4 and also the burner 6 as shown and forms a support for the hopper. 60

Arranged above the top edge 5 of the receptacle 4 is a vertically movable compressed air nozzle 8 having the lower edge thereof beveled and machined as shown at 9, so as to squarely meet the beveled edge 5 of the receptacle 4 and form a tight closure. The nozzle 8 is at the lower end of a tubular stem 10 which extends above the top of the hopper where it is connected to the lower end of a threaded sleeve 11, the same passing through 70 the threaded bore 12 of a bearing member 13 supported upon the top of the hopper 1 or the inclosing jacket 7 thereof. Above the supporting member 13 an operating handle or lever 14 is fastened to the pressure screw 75 or threaded bearing 11 so that by moving said handle 14 to the right or to the left, the nozzle 8 is raised and lowered for the purpose of admitting molten metal from the hopper 1 to the receptacle 4 and cutting off the 80 flow. The tubular stem of the hopper 1 extends fixedly through the pressure screw or threaded sleeve 11 into the lower end of a compressed air valve casing 15 containing a compressed air valve 16 of the two-way 85 type and controlled by an outwardly extending handle or lever 17 arranged over the handle or lever 14. The valve 16 has a main air passage 18 extending diametrically therethrough and a radial exhaust passage 19 at 90 a right angle to and intersecting the passage 18. By shifting the handle 17, air may be allowed to pass from a compressed air supply pipe 20 through the valve 16 to the nozzle 8 to force the molten metal from 95 the receptacle 4 through the outlet or transverse charging nozzle or nozzles 3 to the die or dies. By shifting the handle 17 to another position, the compressed air in the machine is allowed to escape in the passage 100 19 to the atmosphere.

I claim:—

1. In a die casting machine, the combination of a metal hopper, having a metal holding receptacle of a predetermined size in the bottom portion thereof and also having an outlet conduit leading off from said receptacle, supporting means for said hopper, a compressed air supply pipe, an enlarged compressed air nozzle at the discharge end 110 of said pipe, means for shifting said nozzle into and out of contact with an edge of said

metal receptacle to control communication between said hopper and receptacle, and means for controlling the admission of compressed air to said compressed air nozzle.

- 5 2. In a die casting machine, the combination of a metal hopper, having a metal holding receptacle of a predetermined size in the bottom portion thereof and also having an outlet conduit leading off from said receptacle, supporting means for said hopper, a compressed air supply pipe, an enlarged compressed air nozzle at the discharge end of said pipe, means for shifting said nozzle into and out of contact with an edge of said metal receptacle to control communication between said hopper and receptacle, means for controlling the admission of compressed air to said compressed air nozzle, the nozzle adjusting means comprising a threaded member having a fixed relation to the stem of said nozzle, a bearing member in which said threaded member is held, and manually operable means for turning said threaded member to raise and lower said compressed air nozzle.
- 10 3. In a die casting machine, the combination of a metal hopper, having a metal holding receptacle of a predetermined size in the bottom portion thereof and also having an outlet conduit leading off from said receptacle, supporting means for said hopper, a compressed air supply pipe, an enlarged
- 15
- 20
- 25

compressed air nozzle at the discharge end of said pipe, means for shifting said nozzle into and out of contact with an edge of said metal receptacle to control communication between said hopper and receptacle, and means for controlling the admission of compressed air to said compressed air nozzle, the meeting edges of said compressed air nozzle and metal receptacle being beveled and machined.

4. In a die casting machine, the combination of a metal hopper, having a metal holding receptacle of a predetermined size in the bottom portion thereof and also having an outlet conduit leading off from said receptacle, supporting means for said hopper, a compressed air supply pipe, an enlarged compressed air nozzle at the discharge end of said pipe, means for shifting said nozzle into and out of contact with an edge of said metal receptacle to control communication between said hopper and receptacle, and means for controlling the admission of compressed air to said compressed air nozzle, said air controlling means embodying a two way valve having a passage to admit compressed air to said compressed air nozzle and another to liberate the compressed air from said nozzle.

In testimony whereof I affix my signature.

JAMES BATE.
